UNITED STATES PATENT OFFICE.

WILLIAM D. FORSYTH, OF YOUNGSTOWN, OHIO, ASSIGNOR, BY MESNE ASSIGNMENTS, TO RAILWAY PRODUCTS CORPORATION, OF BUFFALO, NEW YORK, A CORPORATION OF NEW YORK.

REMOVABLE ASSEMBLED DRAFT-GEAR.

1,130,386.

Specification of Letters Patent.

Patented Mar. 2, 1915.

Application filed March 31, 1913. Serial No. 757,812.

To all whom it may concern:

Be it known that I, WILLIAM D. FORSYTH, a citizen of the United States, residing at Youngstown, in the county of Mahoning and State of Ohio, have invented new and useful Improvements in Removable Assembled Draft-Gears, of which the following is a specification.

My invention relates to improvements in draft gears for use on railway cars.

The principal objects of my invention are, among other things, to provide a draft gear whose parts can be readily assembled, and when assembled, separated from one another without a complete distribution of the several devices entering into any particular part of it, and at the same time be applied to cars when the parts thereof are assembled with relation to one another; also to provide a draft gear wherein the parts that are subject to tension when said gears are in operation on the cars, are constructed of rolled metal sections, and the parts that are subject to compression under like circumstances are constructed of cast metal.

My invention consists of the removable assembled draft gear hereinafter described and claimed.

Like figures of reference refer to like parts throughout.

Figure 1 represents a vertical top plan view of my improved draft gear as the same would appear mounted between the draft sills of a car, the said draft sills being partly in section. Fig. 2 is a vertical longitudinal section of Fig. 1 on section line 1—1. Fig. 3 is a vertical longitudinal section similar to Fig. 2, showing a modified construction.

In Fig. 1; 1, 1, are draft sills having holes 2, 2, pierced therein. 3, 3, are bars bolted to the bottom flanges of 1, 1, by tap bolts 4, 4, which support the draft gear between the sills when mounted on the car. 5, 5, 5, 5, are cleats fixed to the web of sills 1, at suitable distances, as shown in the drawings, preferably by riveting the same thereto. In Figs. 1 and 2, 6 is a draw bar yoke formed from a single piece of rolled metal, preferably steel, having shoulders at 7 and 8. 9 is a casting, having flanges 10, 10, and compartments 11, 11, 11, which are formed between the ends and sides of 9 by abutments 12, 12. Casting 9 is countersunk at 13, and has a hole at 14, abutments 12, 12,

have holes 15, 15. 16 is a bar or a pipe, (shown in the drawings as a pipe) insertible in the casting and its abutments as shown in Figs. 2 and 3. 17 is a part of a draw bar of the ordinary construction, with the coupler end not shown, having a hole 18 and a shoulder 19. 20 is a pin adapted to be passed through hole 18 of draw bar 17, having cotter pins 21, 21. 22 is a rectangular link or collar of sufficient size to pass over the front ends of yoke 6. 24, 24, 24, 24, 24, 24, are follower plates or spring seat plates, having holes 25 for the passage of bar or pipe 16. 26, 26, 26, are spiral springs adapted to abut upon the follower plates 24, and to be mounted upon pipe or bar 16. Follower plates 24 abut at each of their edges against cleats 5, fastened to webs of draft sills 1, 1.

In Fig. 3, the draw bar yoke equivalent to the draw bar yoke 6 of Figs. 1 and 2 is composed of two pieces, 27, 27, each having extensions 28, 28, each extension having hole 29, 29, said pieces of said yoke bar being connected at its rear end by pin 30, 80 which is held in place by cotter pin 31. The front ends of said draw bar yoke 27, Fig. 3, are connected by a collar 22, and draw bar 17 is inserted in the same method or manner as draw bar 17 of Figs. 1 and 2. 85

In assembling the parts of the draft gear shown in Figs. 1 and 2 of the drawings, follower plates and springs are mounted in pipe 16 and are placed in the compartments of the block or spring case, where they are centered by putting the bar or pipe 16 through the holes in the rear end of the block and its several abutments and into the socket at its front end. When the yoke is composed of a single rolled metal piece, 95 its front ends are sprung sufficiently to permit them to pass between the flanges of the block, so that the intermediate shoulders of the yoke abut the front end of the block. The flanges of the block prevent the yoke 100 from slipping off the block. The collar is passed over the rear end of the draw bar. The rear end of the draw bar is then placed between the front end of the block and the terminal shoulders of the yoke. Then the 105 collar is passed back over the ends of the yoke and fastened in place by a pin passing through the perforation of the draw bar. The assembled draft gear is now a unit which can be handled, transported, taken 110

off and put on cars without disturbing its different parts in their relations to one another until intentionally separated. The removing or fixing of the support bars of the 5 lower flanges of the draft sills of the car is all that is necessary to be done to permit the assembled draft gear to be put on or taken off the car on which it is to be used. Where the yoke is constructed as shown in 10 Fig. 3, the two yoke side bars are assembled in a manner that is obvious from their shape and construction. When the two piece yoke bar is thus assembled and used, the assembling of the rest of draft gear is 15 substantially the same as in the case where the yoke is constructed as shown in Figs. 1 and 2.

While I have shown but a single spiral spring in each compartment of the block in 20 the drawings, one or more of said springs may be in each compartment of the block without departing from the spirit of my invention.

What I claim as my invention is:

25 1. A draft gear comprising a spring case having compartments therein, a draw bar yoke mounted on said spring case and having shoulders abutting the front end of said spring case, the end portions of said yoke 30 extending beyond the front end of said spring case, the ends of said end portions of said yoke being inturned toward each other, a draw bar mounted between said end portions and having shoulders engaging said 35 inturned ends, said draw bar being in contact with the front end of said spring case, and detachable means for holding said yoke in place on said draw bar.

2. A draft gear comprising a draw bar 40 yoke having the ends thereof inturned toward each other, a spring case removably mounted in said yoke, a draw bar mounted between the end portions of said yoke and

having shoulders engaging said inturned ends of said yoke, said draw bar being in 45 contact with the front end of said spring case, a removable collar surrounding said end portions of said yoke and retaining said yoke in position on said draw bar, and a removable pin passing through said draw bar 50 and holding said collar in place.

3. In a draft gear, a draw bar yoke, a draw bar removably secured to said yoke, and a spring case removably mounted in 55 said yoke and bearing against said draw bar and said yoke, said spring case having two flanges projecting from each of two opposite longitudinal faces thereof, said yoke lying between said flanges.

4. In a draft gear, a draw bar yoke, a draw bar removably secured to the ends of 60 said yoke, a spring case removably mounted within said yoke and bearing against said draw bar, said spring case having compartments therein, a pair of follower plates in 65 each of said compartments, a spring between each pair of said follower plates, and a removable rod extending longitudinally of said spring case through said follower plates and said springs. 70

5. In a draft gear, a draw bar yoke, a spring case removably mounted within said 75 yoke, said spring case having compartments therein, a pair of follower plates and a spring in each of said compartments, and a removable rod extending longitudinally of said spring case through said follower plates and said springs.

In witness whereof I have hereunto set my hand in the presence of two subscribing 80 witnesses.

WILLIAM D. FORSYTH.
